(No Model.)

G. W. DAY.

FOUNTAIN ATTACHMENT FOR WASH BOILERS.

No. 399,845.

Patented Mar. 19, 1889.

UNITED STATES PATENT OFFICE.

GEORGE WASHINGTON DAY, OF LANSING, KANSAS.

FOUNTAIN ATTACHMENT FOR WASH-BOILERS.

SPECIFICATION forming part of Letters Patent No. 399,845, dated March 19, 1889.

Application filed October 18, 1888. Serial No. 288,496. (No model.)

To all whom it may concern:

Be it known that I, GEORGE WASHINGTON DAY, a citizen of the United States, residing at Lansing, in the county of Leavenworth and 5 State of Kansas, have invented certain new and useful Improvements in Fountain Attachments for Wash-Boilers; and I do hereby declare the following to be a full, clear, and exact description of the invention, such as will 10 enable others skilled in the art to which it appertains to make and use the same.

This invention relates to wash-boilers of that class wherein a circulation of water through the clothes is effected, the hot water 15 at bottom of boiler being raised by the generation of steam and poured in a cascade over the clothes in the boiler; and it has for its object to provide a simple, durable, and effective apparatus of the class named in 20 which a central heating-chamber is isolated from the points at which the returning current first enters the channels leading to said central chamber and is thoroughly heated again before entering said chamber on its way 25 to the outlet-tube; and it consists of the parts and combinations of parts hereinafter described and claimed.

In the accompanying drawing, forming a part of this specification, is illustrated a perspective view of my device, looking at the bottom or lower part of the same.

A represents the base-plate of the apparatus, of such size and form as to fit the interior of a boiler; and B, a flange secured to the 35 edge of said plate in any desired manner and extending downwardly therefrom and forming the outer wall of channels *a* and *b*, the inner walls of said channels being formed by the curved partitions *c* and *d*. The channels 40 *a* and *b* are separated by short partitions *e*, which extend across the center of the plate A from each side to the straight partitions *f*, which extend lengthwise the plate and form the walls of the heating-chamber. At each 45 end the partitions *f* are cut away or reduced, as at *g*, and a short channel, *h*, is formed between said partitions and the curved partitions *c* and *d*. The ends of the curved partitions do not extend to the partitions *e*, a 50 space or opening being left between them, so

that communication may be had between the channels *a* and *h*. All of the partitions are of the same width as the flanges B, so that when the device is in position in a boiler the channels *a*, *b*, and *h* are practically closed 55 passages which only communicate through the openings at the ends of the curved partitions. By this construction a large chamber is provided at the center of the device, where the bulk of the water will be heated 60 and the steam generated, communication with which can only be had from the channels by the contracted openings formed by the reduced ends of the straight partitions *f*. From the center of the base-plate A a 65 tube, C, projects, having a cross-tube, D, at its end, and at each end of the device a series of perforations, E, is formed in the channels *a* and *b* through the base-plate, through 70 which the water finds its way to said channels. The cross-tube D is telescoped on tube C and may be adjusted in or out, as desired, as indicated by dotted lines in the drawing.

In operation the apparatus is fitted accurately within a wash-boiler about two-thirds 75 filled with water, soap added, and the clothes placed on top of the device and pressed down. When the boiler thus prepared is placed upon a hot fire and the water brought to the boiling-point, the steam generated will find its 80 escape from the central chamber through the tube C, and when sufficiently strong it forces the water along with great rapidity through said tube and out on the clothes. The supply of water to the central space for the generation of the steam is kept up by the water in the boiler passing through the perforations E into channels *a* and *b* and along the same into the channels *h*, and from thence through 85 the openings at the ends of the straight partitions *f* into the chamber.

It will be noticed that the water is returned to the apparatus at the greatest distance from the central tube, thus causing it to move a long distance over the highly-heated bottom 95 of the boiler before entering the chamber, and thus becoming heated and making a greater supply of steam and producing a more rapid current of water. The cross-tube D may be drawn out in order to increase the 100

distance the water must travel through the clothes in order to return to the apparatus, and thus hasten the process of cleansing.

The arrangement of the partitions is intended to prevent the escape of the steam through any other exit than the tube C; but should any steam escape from the heating-chamber to channel h it will be met by the current of water entering said channel, and must force the same back through the somewhat complex passage formed by the channels and overcome the weight of water entering the same through the perforations E before it can change the direction of the current. The reduction of the ends of the partitions f at g admits a flow of water into the heating-chamber, but retards a counteraction in the downward current, as the heated water rising meets the obstruction formed by the end of

the partitions f and naturally finds its way to 20 the tube C.

Having thus described my invention, what I claim as new, and desire to secure by Letters Patent, is—

The combination of the base-plate having 25 the perforations therethrough near its ends, the flange secured to the edge of said plate, the curved partitions c and d, the short partitions e, the straight partitions f, having their ends reduced, the tube C, and the cross-tube telescoped on said tube C, substantially as described.

In testimony whereof I affix my signature in presence of two witnesses.

GEORGE WASHINGTON DAY.
